UNITED STATES PATENT OFFICE.

STEPHEN J. GUARNERI, NOW BY JUDICIAL CHANGE OF NAME STEPHEN J. GARY, OF NEW YORK, N. Y., ASSIGNOR OF ONE-HALF TO JOHN E. LEWIS, OF NEW YORK, N. Y.

CROSS-JOINTED METAL BAR.

Application filed March 18, 1925. Serial No. 16,450.

This invention relates to cross-jointed metal bars and particularly to a joint structure for metal window sashes, metal doors carrying panes of glass and other structures and has for an object to provide a construction which will present a maximum strength and a pleasing appearance.

Another object in view is to provide a joint structure for metal bars wherein none of the metal is removed or a minimum amount is removed.

A further object of the invention is to provide a cross-joint structure for bars for metal window sashes and the like wherein part of one bar is cut and pressed into a bracing and holding member interlocking with certain parts of the crossing bar.

In the accompanying drawings—

Figure 1 is an elevation of a metallic window sash showing other cross-joints embodying the invention.

Figure 2 is an enlarged elevation of one of the cross-joints shown in Figure 1.

Figure 3 is a side view of the vertical bar shown in Figure 2 before the pressed out portion has been formed into its final shape.

Figure 4 is a sectional view through Figure 2, on line 4—4.

Figure 5 is a sectional view through Figure 2, on line 5—5.

Figure 6 is a perspective view of the interlocking part of the bar shown in Figure 2 illustrating how the same is formed to receive the cross bar.

Figure 7 is a view similar to Figure 5 but showing a modified construction, the same being taken approximately on line 7—7 of Figure 8.

Figure 8 is a view similar to Figure 4 but showing a modified construction.

Figure 9 is a view similar to Figure 8 but showing a further modified construction.

Figure 10 is a top plan view of Figure 9.

Figure 11 is a sectional view through Figure 9, approximately on line 11—11.

Referring to the accompanying drawings by numerals, 1 indicates a metal frame of any desired kind having cross bars 2 and 3 for assisting the frame 1 in holding the different panes of glass 4 in proper position. Heretofore, various methods have been provided for interlocking and connecting together at the point of crossing the bar 3 with the various bars 2. In the present invention, an improved structure has been pro-

vided shown in its complete working condition in Figures 2, 4 and 5.

From Figure 3 the bar 2 is shown after it leaves the first die or punch. In this condition, a section 5 is pressed away from the web 6 for forming a socket 7. The section is cut out of the web 6 to form the slot 8 and a portion is pressed out of the web at point 9 for forming the bracing members 10 and 11 which are integral as they are pressed from the same piece of material. After the parts have been thus formed, the bar 3 is forced into position as shown in dotted lines in Figure 3 and then a die is used for pressing and forming the apex or connecting portion 12 until the stiffening and gripping channel 13 is formed and is caused to press against the edge of the web of bar 3 and also against part of the sides thereof.

When the parts are in the position shown in Figures 2 and 4, the bar 3 is held rigidly in place without any auxiliary holding means. It will be noted that in forming this cross-joint, the only metal actually removed is that which is removed to form the slot 8. By this method of construction, the cross-joint has almost one hundred per cent of metal left in place and acting to brace or stiffen the joint. From Figures 3, 4 and 6, it will be noticed that the line of severance 14 is about centrally of the web 6 but if desired, this line could be raised or lowered in respect to the base 15 of bar 2 without departing from the spirit of the invention.

In the form of the invention shown in Figures 2 to 6, the gripping member 13 projects above the web of bar 2 for approximately the thickness of the metal. Under some circumstances it is desired to make the structure so that the upper edge of the gripping member 11 will be flush with the edge of the bar 2. When this is the case the parts are constructed as shown particularly in Figures 7 and 8. From these figures it will be noted that the bar 3 is formed with a notch 16 which is adapted to receive the gripping member 13' which is formed in exactly the same manner as gripping member 13 but is pressed downwardly until it assumes the position shown in Figure 8. In constructing this form of the invention, the portion or apex 12 must be raised substantially to the position shown in Figure 3 in order that bar 3 of Figure 7 may pass through until notch 16 is in a correct position.

tion after which the gripping member 13 may be formed and may be pushed down into the notch 16 until the parts are flush as shown in Figure 8. This positively locks all the parts together and also presents a stiffened and braced structure at the cross-joint which heretofore has been the weakest part of the window sash.

In Figures 9, 10 and 11, a further modified form of the invention is shown in which a bar 8' having a face of a different shape is shown though the same form of base as shown in Figure 4 might be used with this form of the invention. In this form of the invention, a web is cut from the base along the line 17 and is formed into the bracing members 10' and 11' after which the gripping member 13'' is pressed into the desired shape and desired position. In this form of the invention, none of the material of either bar is removed and, consequently, this presents a very strong and rigid cross-joint which retains one hundred per cent of the material of which the bars are made. It is evident that other forms of the invention might be made without departing from the spirit of the invention, the essential principle remaining the same. Heretofore, either one or both bars have been notched and the parts interlocked either with or without some form of solder or fastening means. In the present invention, very little or none of the metal is entirely removed but, on the contrary, a portion of one of the bars is pushed to one side and formed into gripping and bracing members for not only bracing the bar on which the members are formed but the cross bar co-acting therewith.

What I claim is:

- 40 1. In a cross-joint for bars, a substantially T-shaped bar formed with a base having a pressed out portion spaced from the web of the bar, said bar being formed with a slot extending at right angles to the base opposite the center of the pressed out portion, said slot extending an appreciable distance toward the outer edge of the web of the bar, and a bracing and gripping structure substantially U-shaped in cross section pressed from the web so that the gripping structure will grip the outer edge of the web of a co-acting bar having its base fitted into said pressed out portion, said gripping structure extending an appreciable distance at right angles to the web from which it is pressed and in a direction parallel to said co-acting bar.
- 45 2. In a cross-joint for T-shaped metal bars, a bar having a portion of the web pressed out for forming a gripping member formed to engage the outer edge and part of the sides of the web of a co-acting T-shaped bar, and a pair of diagonally positioned bracing members bracing said member and the co-acting bar.

3. A cross joint structure for window sash bars and other devices, comprising a pair of T-shaped bars, one bar being formed with an opening therein through which the other bar extends, the bar with the opening being 70 also formed with a gripping channel member extending laterally thereof for gripping the web of the other bar, and bracing means extending from said gripping channel and merging into the web of the bar having the 75 opening therein for firmly holding the channel member in a predetermined position.

4. In a cross joint for metal bars, a T-shaped bar formed with a base and a web, said web being provided with an opening for receiving another T-shaped bar extending at an angle to the first bar, said first bar being formed with a pair of diagonally positioned bracing members merging into the web of the bar and also into a substantially 85 channel-shaped stiffening and gripping member extending laterally at an angle to the bar from which it is pressed for gripping part of the web of the other T-shaped member when the two parts are assembled. 90

5. In a cross joint for metal bars, a substantially T-shaped bar provided with a portion of the base pressed away from the web, said bar being formed with a slot extending at right angles to the web opposite the center of the portion pressed away from the web, a pair of diagonally positioned bracing members pressed from said web and formed at the meeting points with a substantially channel-shaped gripping member, the 95 opening formed by the pressing of said bracing members from the web merging into said slot whereby another T-shaped bar may be positioned with parts of its web fitting into said slot and the outer edge of the web projecting into said channel-shaped member while the base is fitted into the space provided by the pressed out portion of the base of the first mentioned T-shaped Bar. 105

6. A cross joint for metal bars, comprising a pair of substantially T-shaped metal bars, one of said bars having a web formed with a notch in the outer edge of its web and the other of said bars having openings for receiving the first bar as it extends through the second bar, said second bar being formed with pressed out members presenting oppositely extending bracing members merging into a gripping channel member extending at an angle to the bar from which it is pressed and straddling part of the web of the first bar for locking the two bars together. 110

7. In a cross joint for bars, a substantially T-shaped bar formed with a base having a pressed out portion spaced from the web of the bar, said bar being formed with a slot extending at right angles to the base opposite substantially the center of the pressed out portion, said slot extending an appreciable 125 distance, 130

distance toward the outer edge of the web of the bar and a laterally projecting bracing and gripping structure pressed from the web so that the gripping structure will grip the edge of a co-acting bar having its base fitted into said pressed out portion.

8. In a cross joint for metal bars, a bar perforated between its edges to permit insertion therethrough of a cross bar, the material of said first bar adjacent the perforation being laterally displaced and formed to engage the second bar laterally of said first bar to effect bracing of said bars by material displaced out of normal position.

9. In a cross joint for metal bars, a bar 15 perforated between its base and the edge of its web to permit insertion therethrough of a cross bar having a co-operating base and web, the web material of said first bar adjacent the perforation being laterally displaced 20 and formed to engage the web of the second bar laterally of the web of said first bar to effect bracing of said bars by web material displaced out of normal position.

STEPHEN J. GUARNERI,
